(57) CLAIM

The ornamental design for a VR mask set, as shown and described.

DESCRIPTION

FIG. 1 is a perspective view of a heat dissipating component of a VR mask set showing my new design, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a mask body of the VR mask set, shown separately for ease of illustration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof;

FIG. 17 is a perspective view of the VR mask set;

FIG. 18 is a perspective view of the VR mask set; and,

FIG. 19 is an enlarged view of portion 19 shown in FIG. 1. The dash-dash broken lines in the drawings depict portions of the VR mask set that form no part of the claimed design. The dot-dash broken lines represent boundaries of the enlarged portion and form no part of the claimed design.
